SEWING MACHINE GEAR-LUBRICATING
SYSTEM

Richard Kaier, Cranford, N. J., assignor to The
Singer Manufacturing Company, Elizabeth,
N. J., a corporation of New Jersey

Application June 25, 1937, Serial No. 150,224

5 Claims. (Cl. 184—6)

This invention relates to sewing machines having gear-connected rotary shafts. A machine of the type in question is disclosed, for example, in United States patent of Philip Diehl, Re. 16,119, 5 reissued July 21, 1925. In this machine the top and bottom pairs of gears are lubricated by a semi-fluid lubricant, as grease or Vaseline, contained in two separate gear-cases. Such a machine, when commercially used at speeds above 10 4000 stitches per minute suffers from rapid deterioration and destruction of the gears, particularly the top gears, and much time and effort has been expended in unsuccessful attempts to overcome the difficulty.

15 After having thoroughly canvassed the various possibilities of gear failure, such as shaft whip, improper tooth-shape, etc., it has finally been discovered that lack of adequate lubrication is the chief cause of gear-failure at high operating 20 speeds.

The present invention has for an object to provide a simple and practical system for adequately lubricating the gears of a high-speed sewing machine so that the machine can be commercially 25 operated at speeds which have heretofore caused premature destruction of the gears.

A further object of the invention is to provide a gear-lubricating system which is economical of lubricant and cool-running, and which only requires the occasional attention of an operator to 30 maintain it in efficient operative condition.

Still further, the invention has for an object to provide a gear-lubricating system which is practically leak-proof and is applicable to a sewing 35 machine of conventional design.

With the above and other objects in view, as will hereinafter appear, the invention comprises the devices, combinations and arrangements of parts hereinafter set forth and illustrated in the 40 accompanying drawings of a preferred embodiment of the invention, from which the several features of the invention and the advantages attained thereby will be readily understood by those skilled in the art.

45 Fig. 1 is a side elevation, partly in section, of a sewing machine embodying the invention. Fig. 2 is a section on the line 2—2, Fig. 1. Fig. 3 is a section on the line 3—3, Fig. 1. Figs. 4 and 5 are, respectively, disassembled perspective views 50 of the bottom and top gear-cases shown in Figs. 1, 2 and 3. Fig. 6 is a top plan view of the top bearing bushing for the vertical shaft of the machine, and Figs. 7 and 8 are sections on the lines 1—7 and 8—8, respectively, Fig. 1.

55 Referring to the drawings, 1 represents the

bed of the sewing machine frame upon which stands the upright member or standard 2 of the gooseneck 3 terminating in the head 4 which carries the usual reciprocatory needle-bar 5, needle 6, presser-foot 7, take-up 8 and tension-device 9.

Journalized in the gooseneck 3, in the end ball-bearings 10, 11 and intermediate bearing 12 is the upper horizontal rotary main shaft 13 which at its forward end is connected in the usual manner to drive the needle-bar 5 and take-up 8. This shaft carries the usual feed-lift eccentric 14 and feed-advance eccentric 15 which drive the usual four-motion feed-dog (not shown).

Journalized below the bed 1, in the cylindrical bearing bushings 16, 17 is the lower rotary shaft 18 which carries the usual rotary hook device 19 complementary to the needle 6 in the formation of stitches.

Journalized in the standard 2, in the cylindrical bearing bushings 20, 21, is the upright tubular shaft 23 which is formed externally at its lower end with a spiral oil-pumping groove 24 working in the pump-cylinder 25 fixed in the pump-well 26 in the bottom section 21 of the horizontally 25 split lower gear-casing. The upper section 28 of the lower gear-casing has an aperture 29 which snugly fits over the lower end of the bearing bushing 21. The separable sections 21, 28 part at a plane containing the axis of the shaft 18 and 30 normal to the axis of the shaft 23. This provides for a lubricant well below the parting plane and minimizes the risk of leakage. The sections 27, 28 may be elongated transversely of the machine bed and are formed with the matched 35 semi-circular openings 30 which are clamped upon the rearward end of the bearing bushing 17 by the fastening screws 30' which secure the gear-case sections together.

The lower gear-case section 27 may be formed with a steady foot 31 which is secured by a screw 32 to the sewing machine frame leg 33. The rearwardly extending portion of the lower section 27 is also formed at the parting plane between the sections 27, 28, with an integral oil-retaining roof or top-wall 34, to prevent possible leakage of oil through a crack at the parting plane when the sewing machine is canted for the usual inspection of the underbed mechanism. The upper section 28 of the lower gear-case is formed with an aperture 35 entered by the tube 36 extending downwardly through the machine bed 1. A gauge stick may be inserted in the tube 36 to test the level o—o of oil in the sump of the lower gear-case. The lower gear-case 27, 28 55

encloses the lower pair of bevel gears 37, 38 fixed to the shafts 18 and 23, respectively.

The upper pair of gears 39, 40 are fixed, respectively, to the main shaft 18 and upright shaft 23. These gears are enclosed by the horizontally split upper gear-casing, the sections 41, 42 of which are secured together by screws 43 accessible through the specially provided screw-driver holes 43' in the gooseneck.

10 The upper gear-case sections 41, 42 are clamped together upon and grip the reduced end 44 of the frame bushing 45. They also closely but freely embrace the cylindrical hub of the gear 39. The lower section 42 of the upper gear case has a circular or tubular downwardly extending portion 46 which is received in the flanged head 47 of the bushing 20.

15 The bushings 20, 21 are formed with longitudinally extending oil-return ducts 48 along-side and in communication with the bearings for the upright shaft 23, so that such shaft bearings will be thoroughly lubricated by the return stream of oil. The bushings 20 and 21 are connected together by the tube 49 which is concentric with the upright shaft 23.

20 When the machine is in operation, the rotation of the spirally grooved upright shaft 23 forces the fluid oil in the sump downwardly in the pump-cylinder 25 to the pressure chamber 50 from which the oil flows upwardly through the hollow upright shaft 23 and out of the upper end of such shaft within the circle of teeth of the bevel gear 40. As the oil emerges from the upper end of the shaft 23 it is thrown by centrifugal force radially outwardly of the gear body 40, as a sheet of oil, simultaneously in all directions in the plane thereof, and floods the teeth of such gear, as well as the meshing teeth of the companion gear 39 at the instant of contact, so that the oil is applied where it is needed before it is thrown off of the teeth by centrifugal force.

25 The oil, after flooding the teeth of the gears runs down through the outlet 46 into the flanged head 47 of the bearing bushing 20 and through the oil-return duct 48 therein to the tube 49 through which it flows to and through the duct 48 in the bushing 21 and into the lower gear-case 27, 28. Return oil from the lower duct 48 floods 30 the lower gears 37, 38 sufficiently to prevent permanent destruction thereof. These lower gears are not subjected to the destructive wear to which the upper pair of gears are subjected and hence do not require to be radially flooded. There is 35 an oil mist created by agitation of oil by the gears in the lower gear-case which is also helpful in lubricating the lower gears.

40 The gear-cases are preferably die-cast from any suitable material and the lower gear-case is preferably elongated crosswise of the machine-bed to increase its oil-capacity.

45 The invention is not to be understood as limited to the details of construction and relative arrangements of parts shown and described, as various modifications may be readily made, by those skilled in the art, within the spirit and scope of the invention.

Having thus set forth the nature of the invention what I claim herein is:

50 1. A sewing machine having a frame including a bed and a gooseneck, lower and upper rotary shafts journaled in said bed and gooseneck, an

upright shaft having an external spiral oil-pumping groove at its lower end and an internal oil-delivery duct in communication with said groove and leading to and through the upper end of said upright shaft, lower and upper gear-connections between said upright shaft and said lower and upper shafts, lower and upper gear-housings separate from said frame and enclosing said gear-connections, a pump-cylinder embracing the spirally grooved portion of said upright shaft within said lower gear-housing, and an oil-return connection from the upper to the lower gear-housing.

2. A sewing machine having a frame including a bed and a gooseneck, lower and upper rotary shafts journaled in said bed and gooseneck, vertically aligned bearing bushings mounted in said gooseneck and formed internally with oil-return ducts, a hollow upright shaft journaled in said bushings, lower and upper gear-connections between said upright shaft and said lower and upper shafts, lower and upper gear-housings separate from said frame and enclosing said gear-connections, means in said lower gear-housing to pump oil upwardly through said hollow upright shaft to the gears in said upper gear-housing, and return means to conduct oil from the upper gear-housing downwardly through said vertically aligned bearing bushings to the lower gear-housing.

3. The combination with three shafts, two pairs of bevel gears interconnecting said shafts, and two substantially oil-tight split gear-housings detachably enclosing said pairs of bevel gears, of an oil-pump driven by one of said shafts in one of said gear-housings, means to conduct oil from said pump to the other gear-housing, and oil-return means leading from the other gear-housing to the gear-housing containing the oil-pump.

4. A sewing machine having a frame including a bed and a gooseneck, lower and upper rotary shafts journaled in said bed and gooseneck, an upright shaft, lower and upper gear-connections between said upright shaft and said lower and upper shafts, lower and upper gear-housings separate from said frame and enclosing said gear-connections, and means to circulate oil to-and-fro between said gear-housings, said lower gear-housing being split horizontally into two detachably connected sections elongated transversely of the machine bed, the rearwardly disposed portion of the lower section having an integrally formed roof-portion at the parting plane between said sections.

5. In a sewing machine, the combination with two horizontal parallel shafts, an open-ended tubular vertical interconnecting shaft at right angles thereto, and two pairs of bevel gears connecting said shafts, of two substantially oil-tight split gear-housings detachably enclosing said pairs of bevel gears, the lower one of said gear-housings being formed in its bottom wall with a downwardly projecting closed bottomed pump-cylinder, the lower end-portion of said tubular shaft being externally spirally grooved and projecting into said pump-cylinder but terminating short of the lower closed end of the latter, and an oil-return duct leading from the upper to the lower gear-housing.

RICHARD KAIER.
